(57) **CLAIM**

The ornamental design for a carrying case, as shown and described.

DESCRIPTION

FIG. 1 is a top, front, right side perspective view of a carrying case in an upright configuration;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom plan view of the carrying case in a spread configuration; and,

FIG. 9 is a top plan view thereof.

The long-dash-short-dash broken lines shown illustrate boundaries of the claim and form no part of the claimed design. The dash-dash broken lines shown illustrate portions of the carrying case that form no part of the claimed design.

1 Claim, 7 Drawing Sheets
